(57) **CLAIM**

The ornamental design for the medical powder delivery instrument, as shown and described.

DESCRIPTION

FIG. 1 is a rear and left perspective view of a medical powder delivery instrument showing my new design;

FIG. 2 is a top plan view of the medical powder delivery instrument of FIG. 1;

FIG. 3 is a bottom plan view of the medical powder delivery instrument of FIG. 1;

FIG. 4 is a front elevation view of the medical powder delivery instrument of FIG. 1;

FIG. 5 is a rear elevation view of the medical powder delivery instrument of FIG. 1;

FIG. 6 is a left elevation view of the medical powder delivery instrument of FIG. 1; and,

FIG. 7 is a right elevation view of the medical powder delivery instrument of FIG. 1.

The broken line showing inside the nozzle is included for the purpose of illustrating environmental structure and forms no part of the claimed design.
